UNITED STATES PATENT OFFICE.

GEORGE M. CHARLES, OF WASHINGTON, DISTRICT OF COLUMBIA.

FOUNTAIN-COMB.

1,005,412.

Specification of Letters Patent. Patented Oct. 10, 1911.

Application filed June 7, 1911. Serial No. 631,833.

To all whom it may concern:

Be it known that I, GEORGE MEADE CHARLES, citizen of the United States, residing at Washington, in the District of Columbia, have invented new and useful Improvements in Fountain-Combs, of which the following is a specification.

The invention relates to that class of combs generally termed "fountain" combs; and consists of a telescopic liquid-container or reservoir in which the inner member, which is spring-pressed, is operated to supply the liquid, through the medium of the teeth, to the scalp and hair of the person using the comb, and to cut off the supply at will.

One of the chief objects of the invention is to provide a simple and inexpensive comb, of the type mentioned, for use in shampooing and otherwise treating the scalp and hair, or, it may be used for cleaning horses, dogs and other animals, suitable liquid compounds being employed for same.

Other objects of the invention will become apparent upon a complete disclosure thereof.

In the drawing—Figure 1 is a vertical longitudinal section of my improved comb; Fig. 2, a transverse section showing the exit to one of the teeth cut off by the inner telescopic member; Fig. 3, a similar view, showing the exit in the inner member in register with the exit in the outer member, whereby liquid may be supplied to the tooth, and Fig. 4 an end elevation of the outer member.

Referring to the several views, the numerals 1 and 2 indicate respectively outer and inner tubular members, the inner member being longitudinally slidable within the outer member. The outer member is closed at one end, and is formed with a boss 3 which is provided with a screw-threaded aperture 4. One end of the inner member is also closed, and has an elongated slot 5 through its wall registering with the aperture 4 of the outer member, and screwed into the aperture 4 is a filling-tube 6, the lower end of which extends into the slot 5 to direct the longitudinal movement of the inner

member, and to limit the extent of said movement, the filling-tube being in communication with the interior of said inner member, which, in conjunction with a small portion of the outer member, serves as a reservoir for the liquid. The outer member is provided with a suitable number of teeth 5, and with a number of small perforations 8, one for each tooth. The inner member is provided with a corresponding number of similar perforations 9 arranged to register with the perforations 8, each of which is 10 arranged immediately in rear of a tooth, so that the liquid will be supplied directly to each tooth. The inner member is normally held in a position to prevent the liquid from flowing through the perforations 8 by a 15 compressible spring 10, but when it is desired to cause the liquid to flow through the perforations 8 it is only necessary to press upon the closed ends of the inner and outer members until the perforations 8 and 9 register, and as soon as the pressure is removed the tensioned force of the spring will return the inner member to normal position, cutting off the flow of the liquid from the reservoir. 75

In operation, after the reservoir has been filled by means of the tube 6, a slight pressure on the end of the inner member will cause the perforations 9 and 8 to register, and as the liquid flows therethrough it will 80 follow the curvature of the teeth, as the perforations 8 are arranged in close proximity to the base of the teeth, the curvature of the teeth therefore is an important feature of my invention, as the flow of the liquid is 85 directed thereby to the point of the teeth, thus dispensing with the employment of tubular teeth.

Having thus fully described my invention what I claim, is— 90

A fountain comb, comprising outer and inner tubular members, the outer member being provided with teeth and with perforations adjacent to said teeth, and the inner member with perforations adapted to register with the perforations in the outer mem- 95

ber, said inner member being provided with a slot and the outer member with a filling-tube extending into said slot, whereby the movement of the inner member is longitudinally guided and limited, and means whereby the inner member may be longitudinally moved to cause the perforations in the respective members to register and to

automatically close the perforations in the outer member.

In testimony whereof, I have hereunto set my hand this 5th day of June A. D. 1911.

GEORGE M. CHARLES.
